UNITED STATES PATENT OFFICE.

RICHARD B. KAIMER, OF NEW HAVEN, CONNECTICUT, ASSIGNOR TO THE ENGLISH & MERSICK CO., OF NEW HAVEN, CONNECTICUT, A CORPORATION.

LATCH FOR VEHICLE DOORS.

Application filed November 29, 1920. Serial No. 427,122.

To all whom it may concern:

Be it known that I, RICHARD B. KAIMER, a citizen of the United States, residing at New Haven, in the county of New Haven and 5 State of Connecticut, have invented a new and useful Improvement in Latches for Vehicle Doors; and I do hereby declare the following, when taken in connection with the accompanying drawings and the characters 10 of reference marked thereon, to be a full, clear, and exact description of the same, and which said drawings constitute part of this application, and represent, in—

Fig. 1 an inside face view of a latch for 15 vehicle doors constructed in accordance with my invention.

Fig. 2 an inside face view of same, partly in sections and showing the locking mechanism in its operating position.

Fig. 3 a similar view showing the locking mechanism in its released position.

Fig. 4 a plan view.

Fig. 5 a front view with the operating lever and lock operating handle broken 25 away.

This invention relates to an improvement in latches for vehicle doors and particularly to latches which are operated from the inside by lever handles and from the outside 30 by rotary spindles.

The object of this invention is to provide means for positively locking the door, which means may be placed in locking position from the inside, so that when the door is 35 closed it can only be opened by one having the proper key to manipulate the lock mechanism and the invention consists in the construction and arrangement of parts as hereinafter described and particularly re- 40 cited in the claim.

In carrying out my invention I employ a latch of common construction including a case plate 10 formed with a front flange 11 through which the usual latch bolt 12 ex- 45 tends. This latch bolt is normally projected by a spring 13 and is operated by a lever handle 14 bearing against an upward projection 15 from the latch bolt and moved against a spring 16 mounted on a guide pin 17. The latch also includes the usual cam 50 18, adapted to be operated from the outside

by a handle spindle entering the hub 19, of the cam. This cam engages with an upward projection 32 from the latch bolt and so that movement of the cam will operate 55 the latch. Pivotedly mounted on the case plate is a locking dog 20 pivoted between the lever handle 14 and the cam 18, the nose 21 extending into the path of movement of and against the cam 18 and in line with the 60 pivotal point 22 so as to form a positive lock for the cam. This dog is provided with an operating handle 23 the vertical movement of which will move the dog into or out of its locking position. This dog is connected by 65 a vertically movable slide 24 located in a groove 25 formed in the case plate and extends below the latch bolt, where it is provided with a stud 26, adapted to be engaged by a roll back 27 operated by a cylinder-lock 70 mechanism 28 of usual construction. Preferably a friction ball latch 29 will be mounted in a fixed block 30, the ball extending into a notch 31 formed for it in the tail of the locking dog. If it is desired to lock the 75 door, when leaving a car, the handle 23 will be depressed so as to move the dog 20 downward into the path of movement of and against the cam 18. This does not prevent the movement of the latch by the lever 80 handle so that the door may be opened in the usual way and when closed from the outside securely locks the door, as the cam cannot be moved when the dog is in its depressed position, and it does not prevent the 85 door being closed, if the dog is turned against the cam when the door is open. To open the door from the outside one must have the proper key to fit the lock 28 so as to lift the slide 24 and force the dog 20 upward out of the path of movement of cam 18 90 so that the latch may be retired by movement of the knob spindle turning the hub 9. I thus provide, in a very simple manner, a positive lock for a vehicle door latch which 95 permits locking the door without the use of a key but which requires the use of a key to open the door from the outside.

I claim:

A latch comprising a case plate, a spring 100 actuated latch bolt mounted thereon, a cam adapted to be turned to move said latch

bolt, a dog pivotally connected to the case plate in line with said cam, a handle pivotally connected with said dog and extending upwardly therefrom, a slide pivotally connected with said dog and a lock mechanism in position to lift said slide and move said dog out of the path of movement of the said cam.

In testimony whereof, I have signed this specification in the presence of two subscribing witnesses.

RICHARD B. KAIMER.

Witnesses:

FRANCIS I. MARTIN,
RUTH E. BRADLEY.
